UNITED STATES PATENT OFFICE.

PAUL MALONEY, OF NEW YORK, N. Y., ASSIGNOR TO INTERNATIONAL DEVICES COMPANY, A CORPORATION OF DELAWARE.

DESIGN FOR A COMBINED CABINET AND STANDARD FOR X-RAY MACHINES.

56,931.

Specification for Design.

Patented Jan. 18, 1921.

Application filed May 25, 1920. Serial No. 384,159. Term of patent 7 years.

To all whom it may concern:

Be it known that I, PAUL MALONEY, a citizen of the United States, residing at New York, New York, have invented a new, original, and ornamental Design for a Combined Cabinet and Standard for X-Ray Machines, of which the following is a specification, reference being had to the accompanying drawing, forming part thereof.

The figure is a perspective view of a combined cabinet and standard for X-ray machines, showing my new design.

I claim:

The ornamental design for a combined cabinet and standard for X-ray machines as shown.

PAUL MALONEY.
